(57) **CLAIM**

The ornamental design for a storage shelf with jars and spoons, as shown and described.

DESCRIPTION

FIG. 1 is a top, front and left side perspective view of a first spoon component of a storage shelf with jars and spoons, showing my new design; the first spoon component being shown removed from the storage shelf with jars and spoons for ease of illustration;

FIG. 2 is a front elevational view of FIG. 1;

FIG. 3 is a rear elevational view of FIG. 1;

FIG. 4 is a left side view of FIG. 1;

FIG. 5 is a right side view of FIG. 1;

FIG. 6 is a top plan view of FIG. 1;

FIG. 7 is a bottom plan view of FIG. 1;

FIG. 8 is a top, front and left side perspective view of a first jar component of the storage shelf with jars and spoons; the first jar component being shown removed from the storage shelf with jars and spoons for ease of illustration;

FIG. 9 is a top, rear and left side perspective view of FIG. 8;

FIG. 10 is a front elevational view of FIG. 8;

FIG. 11 is a rear elevational view of FIG. 8;

FIG. 12 is a left side view of FIG. 8;

FIG. 13 is a top plan view of FIG. 8;

FIG. 14 is a bottom plan view of FIG. 8;

FIG. 15 is a top, front and left side perspective view of a shelf component of the storage shelf with jars and spoons; shown without the jars and spoons for ease of illustration;

FIG. 16 is a front elevational view of FIG. 15;

FIG. 17 is a rear elevational view of FIG. 15;

FIG. 18 is a left side view of FIG. 15;

FIG. 19 is a right side view of FIG. 15;

FIG. 20 is a top plan view of FIG. 15;

FIG. 21 is a bottom plan view of FIG. 15;

FIG. 22 is a top, front and left side perspective view of the storage shelf with jars and spoons in an assembled status,

(Continued)

which consists of three spoon components, three jar components and one shelf component;
 FIG. 23 is a top, rear and left side perspective view of FIG. 22;

FIG. 24 is a front elevational view of FIG. 22;
 FIG. 25 is a rear elevational view of FIG. 22;
 FIG. 26 is a left side view of FIG. 22;
 FIG. 27 is a right side view of FIG. 22;
 FIG. 28 is a top plan view of FIG. 22;
 FIG. 29 is a bottom plan view of FIG. 22;
 FIG. 30 is a top, front and left side perspective view showing the storage shelf with jars and spoons in a use status with H-shaped strips attached to both sides of the shelf component; and,

FIG. 31 is a top, rear and left side perspective view of FIG. 30.

All spoon components are as shown in FIGS. 1-7, all jar components are as shown in FIGS. 8-14, and the shelf component is as shown in FIGS. 15-21, except as shown with the broken line features of FIGS. 30-31. The broken lines in FIG. 15 depict portions of the shelf component of the storage shelf with jars and spoons which form no part of the claimed design. The broken lines, showing the H-shaped strips in FIGS. 30 and 31, represent environment and form no part of the claimed design.
